TRIMMER MECHANISM FOR SEWING MACHINES

Berthold P. Pinkvoss, Bridgeport, Conn., assignor to The Singer Manufacturing Company, Elizabeth, N. J., a corporation of New Jersey

Application March 11, 1939, Serial No. 261,187

7 Claims. (Cl. 112—125)

This invention relates to improvements in trimmer mechanisms for sewing machines and has for its object to provide a simple actuating mechanism for a vibratory trimmer-knife carrier-arm facilitating throwing the trimmer-knife into and out of operation.

The invention consists in the knife-arm actuating mechanism hereinafter described in connection with the accompanying drawing which illustrates a preferred embodiment of the invention and in which:

Fig. 1 shows, in perspective, a sewing machine having the improved trimmer-actuating mechanism. Fig. 2 is an enlarged front elevation of the toggle-link connection between the knife-driving bar and the knife-carrying arm, in the operative position of the toggle-links. Fig. 3 represents a view in side elevation of the knife-arm actuating connections, the needle-reciprocating shaft and the knife-arm being shown in section. Fig. 4 represents a cross-section of the toggle connections on substantially the line 4—4 of Fig. 3. Fig. 5 is a detail view in side elevation of the toggle-link stop-plate. Fig. 6 represents a vertically transverse section of the knife-arm substantially centrally of the knife-arm lifting spring.

The sewing machine illustrated in the drawing has the usual work-supporting bed-plate 1, from one end of which rises the standard 2 of the bracket-arm 3 overhanging the bed-plate and terminating at its free end in a head 4. Rotatably journaled in the bracket-arm 3 is the needle-reciprocating shaft 5 (shown in Fig. 3) connected in any usual or suitable manner with the needle-bar 6 carrying at its lower end the needle 7. The needle-bar 6 is journaled for vertical reciprocation in the usual feed-frame 8, in which is also journaled the feed-bar 9 carrying at its lower end the feeding foot 10. Cooperating with the needle 7 and the feeding foot 10 is the presser-foot 11 attached to the lower end of the presser-bar 12 movable vertically in the bracket-arm head 4.

The trimmer-mechanism includes the commercially well known knife-arm supporting-plate 13 secured in any usual or suitable manner upon the bed-plate 1 adjacent the arm-standard 2 and below the bracket-arm 3, said supporting-plate 13 being preferably adjustable in the usual or any suitable manner lengthwise of the bed-plate 1. The supporting plate 13 has upstanding ears 14 spaced transversely of the bed-plate 1, and pivotally mounted between said ears, as by suitable pintles, is one end of an upwardly arched knife-

arm 15. Suitably secured upon the opposite end of the knife-arm 15 is a trimmer-knife 16 having its operative path of movement adjacent the needle 7, it being understood from the foregoing that the knife-arm 15 vibrates about an axis transverse to the axis of rotation of the needle-reciprocating shaft 5.

Intermediate its ends, the knife-arm 15 has vertically alined bosses 17 and 18 which are apertured to provide a socket 19, Fig. 6. Slidably disposed in said socket 19 is a cupped thrust-tube 20 having a rounded lower end adapted to engage the upper face of the bed-plate 1 under the action of a knife-arm lifting coil-spring 21. When the knife-arm actuating mechanism is disabled, the spring 21 functions to swing the knife-end of the knife-arm 15 upwardly to an extent limited by a stop-screw 22, threaded into an upstanding ear 23 of the knife-arm 15 and adapted to engage the bracket-arm standard 2 in the throw-out position of the trimmer-knife. This knife-arm mechanism is well known in the art and has therefore been herein described in general terms.

Carried by the needle-reciprocating shaft 5 is an actuating element in the form of an eccentric 24 rotatably disposed in a block 25 engaged by a fork 26 of a knife-driving bar 27. The forked bar 27 is guided for vertical reciprocation in a slot 28 provided in the front wall of the bracket-arm 3, said bar 27 being confined to right line reciprocation in said slot 28 by a retainer-plate 29 suitably secured upon the bracket-arm 3. A knife-driving bar of this general type is disclosed in the U. S. patent to A. Rontke, No. 1,200,989, October 10, 1916.

Pivotedly attached to the lower end of the knife-driving bar 27, by a shoulder screw 30, is one end of an upper toggle-link 31 which in its operative position depends generally vertically from the bar 27. Intermediate its ends, the link 31 has an apertured boss 32 into which is threaded a shoulder screw 33 pivotally attaching to the link 31 the upper end of a lower toggle-link 34, disposed adjacent the lower end of the link 31. At its lower end, the link 34 is pivotally connected by a shoulder screw 35 to the knife-arm 15 adjacent the free end of said arm, it being understood that the pivot-screws 30, 33 and 35 are substantially parallel and that the screw 33 connection between the links 31, 34 constitutes the knuckle of the toggle. Furthermore, the hinge-joints of the toggle-links are substantially parallel to the pivotal axis of the knife-arm 15.

Attached by screws 36 to the lower end of the link 31, below the link-connecting screw 33, is an

angular stop-plate 37 provided with a finger-piece 38. The stop-plate 37 has a lateral extension 39 adapted to engage the lower toggle-link 34 thereby to determine the toggle-straightened 5 operative position of the links 31, 34. A bent spring 40 is secured by screws 41 to the stop-plate extension 39, said spring being adapted to yieldingly engage a shoulder 42 on the link 34, thereby yieldingly to latch together the links 31, 34 in 10 the operative position of said links.

It will be noted from Fig. 2 of the drawing that, in their operative position, the links 31, 34 are relatively slightly inclined, i. e., the knuckle or pivot-joint between the two links is disposed 15 slightly at one side of a straight line passing through the pivot-points 30 and 35. Consequently, in the downward movement of the knife-driving bar 27, the stop-plate extension 39 carried by the upper link 31 is forced into positive 20 engagement with the lower link 34 and the two links together constitute a rigid thrust-bar free to swing about the pivot-screw connection 30 with the knife-driving bar. In the upward movement 25 of the knife-driving bar 27, the spring 21 urges the knife-arm 15 upwardly and therefore functions to assist the latch-spring 40 in maintaining the pivotally connected links in their operative relationship.

By a slight pressure against the left hand side 30 of the finger-piece 38, the toggle may readily be "broken," thereby disabling the knife-arm actuating mechanism and raising the knife-end of the knife-arm 15, as illustrated in dotted lines in Fig. 1 of the drawing. The upward swinging 35 movement of the knife-arm is, of course, assisted by the spring 21 which further serves to hold said knife-arm yieldingly in its inoperative position. When bringing the toggle-links 31, 34 again into their operative position, the free end of the 40 knife-arm 15 is at the same time forcibly depressed by the straightening of the toggle-links, the knife-arm depressing power thus available being sufficient to force the knife to sever work in the path of the knife, provided of course that the knife driving-bar 27 is at the lower end of 45 its stroke.

Aside from the simplicity and effectiveness of the above described knife-arm actuating mechanism, a particular advantage resides in the fact 50 that the toggle-link arrangement for throwing the knife-arm into and out of operation permits the hinge-joint 30 to be spaced a substantial distance from the knife-arm 15. In this connection, it is to be understood that, as the knife-arm 15 55 is a vibratory member, the thrust-bar which in the present case is constituted by the two toggle-links 31, 34 has a sidewise swinging movement because of the pivotal connection of the link 34 with the knife-arm. Consequently, a sidewise 60 thrust is imposed upon the knife-driving bar 27 which is largely minimized by spacing the hinge-joint 30 a substantial distance from the knife-arm and by connecting the link 31 to the bar 27 directly adjacent the guiding means for said bar 65 27. Furthermore, the above noted spacing of the hinge-joint 30 from the knife-arm provides for adjustment of the knife-arm lengthwise of the bed-plate without materially affecting the knife-arm actuating connections.

70 Having thus set forth the nature of the invention, what I claim herein is:

1. Trimmer mechanism for sewing machines

comprising, a rotary actuating shaft, a trimmer-knife carrier, an actuating member carried by said shaft, means operatively connected with said member for actuating said carrier including endwise reciprocable toggle-links, said links being 5 relatively movable into and out of toggle-straightened operative position, and manually releasable means for holding said links in the operative position thereof.

2. Trimmer mechanism for sewing machines 10 comprising, a trimmer-knife carrier, an actuating member, a toggle-link connection between said member and carrier, a stop determining a toggle-straightened operative position of said connection, and a latch for releasably holding said 15 connection in the operative position thereof.

3. Trimmer mechanism for sewing machines comprising, a vibratory trimmer-knife carrier, a reciprocating actuating member, means for reciprocating said member, toggle-jointed links 20 connecting said member and carrier, and manually releasable means for holding said links in substantial alinement for transmitting vibratory movements to said carrier from said member.

4. Trimmer mechanism for sewing machines 25 comprising, a pivotally mounted knife-carrier arm, a reciprocating actuating member, means for reciprocating said member, toggle-jointed links 30 pivotally connected to said member and arm, the pivotal axes of said links being disposed substantially parallel to the pivotal axis of said arm, a stop determining a toggle-straightened operative position of said links, and yielding means for releasably holding said links in said 35 operative position.

5. Trimmer mechanism for sewing machines comprising, a trimmer-knife carrier adapted to be thrown into and out of operation, an actuating member, toggle-jointed links operatively connecting said member and carrier in a toggle-straightened operative position of said links, stop means determining an inoperative position of said carrier in a toggle-broken position of said links, and means yieldingly urging said carrier into said 45 inoperative position thereof.

6. In a sewing machine having a bed-plate, a bracket-arm overhanging said bed-plate and provided with knife-driving-bar guiding means, a rotary actuating shaft in said bracket-arm, an actuating element carried by said shaft, a knife-driving bar engaged by said actuating element and confined to right line vertical reciprocation by said guiding means, a trimmer-knife carrier-arm pivotally mounted upon said bed-plate and adapted to be thrown into and out of operation, 50 toggle-jointed links operatively connecting said knife-driving bar and said knife-carrier arm in a toggle-straightened operative position of said links, stop-means determining the operative position of said links, stop-means determining an inoperative position of said knife-carrier arm in a toggle-broken position of said links, and means yieldingly urging said carrier-arm into said 55 inoperative position thereof.

7. Trimmer mechanism for sewing machines 60 comprising, a rotary actuating member, a trimmer-knife carrier, and means for imparting operative movements to said carrier from said member including toggle-jointed and -straightened links, said links being relatively movable out of 70 and into toggle-straightened position thereof.

BERTHOLD P. PINKVOSS.
